METHOD OF MAKING SIGNS

Application filed May 28, 1930. Serial No. 456,787.

This invention relates to the method of making signs.

The main objects of this invention are to provide an improved method of manufacturing sheet metal signs particularly useful for vehicle license plates, highway warning markers, and the like; to provide an improved method of manufacturing a sign having indicia thereon which is of the reflex or light reflecting type, and to provide a method which will fit into a quantity production program so that no operation will delay or hold up the other quantity production operations.

15 This improved method of manufacturing is particularly suitable to making of the sheet metal license plates disclosed in my co-pending application, Serial Number 456,786, filed May 28, 1930, to which reference is hereby made for the purpose of showing a specific embodiment of the product made by the improved method herein set forth.

20 Other objects and features of novelty of my invention will be either specifically pointed out or will become apparent when referring, for a better understanding of my invention, to the following description taken in conjunction with the accompanying drawing, wherein:

25 Figure 1 is a plan view of an element in the nature of a sign embodying features of my invention, and

30 Figs. 2 to 8 inclusive are enlarged sectional views of the structure shown in Fig. 1, illustrating the application of different coatings to the element in accordance with my present method.

35 In the carrying out of my improved method a piece of metal is ground and polished over that portion of a plate 10 in which will be formed the numerals or other indicia 11, for the reason that this may be more easily and rapidly done at this time than after the indicia are formed.

40 The indicia are then formed in the plate, after which it is cleaned, goes through a coppering solution, then through an automatic buffing machine and is then colored and buffed in two directions, then through the nickel, then automatically buffed and colored, then

45 through the chromium, all of which may be done on an automatic conveyor system timed with the speed at which the plates go through the paint and into the ovens.

50 The indicia are then printed with a material 12 which will prevent the adhesion of enamel or other siccative coating 13, after which the plate is placed on the conveyor for painting and goes automatically from the paint to the oven. After coming out of the oven, the paint may be wiped off with a cloth from the indicia, or preferably, it may go directly from the oven into hot water of approximately the same temperature as the plate and forced by conveyor between bristle 55 brushes, which in one operation removes the paint from the polished indicia and removes all traces of the material 12 and paint so removed from the other surfaces of the plate. Then the plate, which tends to dry quickly 60 on account of being hot, may have water blown from its surface by compressed air and be dry for packing.

65 This process has the advantage of enabling the paint to be removed from the indicia 70 without the use of abrasive wheels or solvents, saving these operations, even though the latter were practical and possible.

75 If spraying is used for applying the enamel, the paint used on the rear side of the plate may be saved as the plate is already rust-proofed in the plating process, and in the event of either spraying or dipping for the painting, the operation of printing the top of the indicia with ink as is the present 80 practice is eliminated and hours of time for baking this are saved and the operation of the final varnishing of the plate to protect these printed numerals is also eliminated 85 and the subsequent time for baking and drying is saved, due to the fact that the polished plated indicia needs no further treatment to insure its permanency.

90 If an indicia upon the signs is formed as shown in my above-mentioned co-pending 95 applications, the tops of the semi-frusto-pyramids may be coated with paint or enamel so that the indicia stands out in dotted outline.

95 The fact that these semi-frusto-pyramids

are equally distant and the valleys between them run in only two directions make it possible to use a felt wheel with an abrasive for grinding these if necessary. If the plates 5 are run under the wheel in exactly the same position every time, grooves will be formed in the wheel a depth equal to the height of the pyramids, therefore allowing the grinding or buffing surface of the wheel, which- 10 ever is being used, to bear evenly upon all of the polished surface and not remove the peaks of the deformations.

In Figs. 6, 7 and 8, I have shown the method of painting the surface of the indicia, 15 wherein the indicia have flat surfaces, which method is also employed for painting the frusto-pyramidal surfaces as above mentioned. Upon the hardened coating 13 the material 12 is placed and a layer of paint 14 20 which will ordinarily be different in texture or color from the coating 13, disposed on the plate 10 by spraying, dipping, brushing or the like. Thereafter a drying and a washing operation cleans the plate and the surfaces 25 of the indicia are painted with a different paint from that applied to the background.

Although but one specific method has been herein disclosed, it will be understood that numerous details may be altered or omitted 30 without departing from the spirit of this invention as defined by the following claims.

I claim:

1. The method of making a sheet metal sign which comprises polishing the sheet 35 metal to remove scratches and similar defects, embossing indicia upon the polished portion, coating the indicia with a material which will prevent the adhesion of a siccative coating, applying a siccative coating to 40 the sign and then removing the siccative coating from the indicia.

2. The method of making a sheet metal sign which comprises the polishing of the sheet metal, forming indicia thereon, plating 45 and polishing the indicia to produce a reflecting surface, coating the indicia with a material which will prevent the adhesion of a siccative coating, applying a siccative coating to the sign and then removing the 50 siccative coating from the indicia.

3. The method of making a sheet metal sign which comprises the polishing of the sheet metal, embossing indicia thereon, plating and polishing the indicia to produce a 55 reflecting surface, coating the indicia with a material which will prevent the adhesion of a siccative coating, applying a siccative coating to the sign and then removing the siccative coating from the indicia.

60 4. The method of making a sheet metal sign which comprises the polishing of a portion of the sheet metal, forming indicia upon the polished portion, plating and polishing the indicia to produce a reflecting surface, 65 coating the indicia with a material which

will prevent the adhesion of a siccative coating, applying a siccative coating to the sign and then removing the siccative coating from the indicia.

5. The method of making a sheet metal sign which comprises the polishing of the sheet metal, forming indicia thereon, plating and polishing the indicia to produce a reflecting surface, coating the indicia with a material which will prevent the adhesion of a siccative coating, applying a siccative coating to the sign, and subjecting the sign to heat for drying the siccative coating. 75

6. The method of making a sheet metal sign which comprises the polishing of the sheet metal, forming indicia thereon, coating the indicia with a material which will prevent the adhesion of a siccative coating, applying a siccative coating to the sign, removing the siccative coating from the indicia, and then applying a siccative coating to portions of the indicia. 80

7. The method of making a sheet metal sign which comprises the polishing of a portion of the sheet metal, forming indicia upon the polished portion, coating the indicia with a material which will prevent the adhesion of a siccative coating, applying a siccative coating to the sign, removing the siccative coating from the indicia, and then applying a siccative coating to portions of the indicia. 85

8. The method of making a sheet metal sign which comprises the polishing of the sheet metal, forming indicia thereon, coating the indicia with a material which will prevent the adhesion of a siccative coating, applying a siccative coating to the sign, subjecting the sign to heat for drying the siccative coating, and then applying a siccative coating to portions only of the indicia. 90

9. The method of making a sheet metal sign which comprises the polishing of the sheet metal, forming indicia thereon, plating and polishing the indicia to produce a reflecting surface, coating the indicia with a material which will prevent the adhesion of a siccative coating, applying a siccative coating to the sign, removing the siccative coating from the indicia, and then applying a siccative coating to portions only of the indicia. 115

10. The method of making a sheet metal sign which comprises the polishing of the sheet metal, forming indicia thereon, coating the indicia with a material which will prevent the adhesion of a siccative coating, applying a siccative coating to the sign, washing and scrubbing the sign to remove the siccative coating from the indicia, and then applying a siccative coating to portions only of the indicia. 120

11. The method of making a sheet metal sign which comprises forming indicia thereon having a plurality of reflecting surfaces disposed in uniform rows at varying predetermined angles, coating the indicia with a

material which will prevent adhesion of a siccative coating, applying a siccative coating to the sign, and then removing the coating and material from the indicia.

5 12. The method of making a sheet metal sign which comprises forming indicia thereon having a plurality of reflecting surfaces on each of said indicium, coating the indicia

with a material which will prevent adhesion of a siccative coating, applying a siccative coating to the sign, subjecting the sign to heat for drying the siccative coating and then removing the coating and the material from the indicia. 70
